United States Patent Office

Des. 198,898
Patented Aug. 18, 1964

198,898

SIDE FOR A CRIB OR SIMILAR ARTICLE

Aaron D. Spencer, Longmeadow, Mass. (% Baby Products Corp., 143 Shaker Road, East Longmeadow, Mass.)

Filed Oct. 31, 1963, Ser. No. 77,222

Term of patent 7 years

(Cl. D5—5)

FIG. 1

FIG. 2

FIG. 1 is a front elevational view of a side for a crib or similar article showing my new design, and

FIG. 2 is an end elevational view taken from the left of FIG. 1.

The reverse side of the crib side is the same as shown in FIG. 1.

I claim:

The ornamental design for a side for a crib or similar article, as shown and described.
